UNITED STATES PATENT OFFICE.

LESLIE M. SHERIDAN, OF EL PASO, TEXAS.

ROTARY ENGINE.

1,302,233.

Specification of Letters Patent. Patented Apr. 29, 1919.

Application filed May 31, 1917. Serial No. 171,950.

To all whom it may concern:

Be it known that I, LESLIE M. SHERIDAN, a citizen of the United States, residing at El Paso, in the county of El Paso and State 5 of Texas, have invented a new and useful Rotary Engine, of which the following is a specification.

The device forming the subject matter of this application is adapted to be employed 10 as a rotary engine, as a pump for liquids, as an air compressor, as a vacuum pump and for other purposes, but for convenience in description, it will be presupposed that the structure is employed as a rotary engine.

15 The invention aims to provide novel means whereby rotary movement is imparted to the shaft, and to improve generally and to enhance the utility of devices of that type to which the present invention applies.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without departing from the spirit of the invention.

In the accompanying drawings:—

Figure 1 shows in vertical section, a device constructed in accordance with the present invention, parts appearing in section;

Fig. 2 is a vertical section in which the cutting plane is disposed at right angles to the cutting plane of Fig. 1;

Fig. 3 is a vertical section showing a modified form of the invention;

Fig. 4 is a vertical section of the structure shown in Fig. 3;

Fig. 5 is a horizontal section of the device delineated in Fig. 3, the line 3—3 of 45 Fig. 5 denoting the cutting plane in which Fig. 3 is taken; and

Fig. 6 is a sectional detail illustrating the means whereby rotation is imparted immediately to the shaft.

50 In that form of the invention which is shown in Figs. 1 and 2, there is provided a pair of side plates 3, having sleeves 2. A ring 5 is disposed between the side plates 3 and is attached thereto by securing elements 6. The side plates 3 and the ring 5 form the stator of the engine. A casing 7 is as-

sembled with the stator and includes an edge portion 8 coöperating with the ring 5 of the stator to form a water jacket, the entrance and the exit for which are represented by suitable connections 9 carried by the part 8 of the casing. Disks 10 coöperate with the side plates 3 to form side water jackets.

The sleeves 2 of the stator carry bushings 11 in which is journaled for rotation a shaft 12 carrying a fly wheel 14, the shaft 12 being eccentrically mounted in the stator. The shaft 12 is provided with projecting arms 15.

Disposed within the stator is a pair of pistons, each including a hub 16 and a body 17, the body 17 of one piston overhanging the hub 16 of the other piston, as clearly shown in Fig. 1. The outer edges 18 of the bodies 17 of the pistons are curved to conform to 75 the inner curve of the ring 5 of the stator. The inner edges of the hubs 16 of the pistons are recessed to receive packing rings 19. The outer surfaces of the pistons carry packings 20, pressed outwardly by springs 80 21 to coöperate with the side plates 3. In the ends of the body portions 17 of the pistons are formed recesses 22 which at times coöperate to form an expansion chamber 23, as shown in Fig. 2. The charge in the ex- 85 pansion chamber 23 may be ignited by a plug 24 carried by one of the side plates 3, or in any other suitable manner. One of the side plates 3 is provided with an inlet port 25 and with an exhaust port 26 as indicated in Fig. 2. In the peripheries of the hubs 16 of the pistons, slots 27 are formed. Blocks 28 are adapted to work in the slots 26 and are pivoted at 29 to the pistons. The blocks 29 are provided with guide passages 90 30, receiving the arms 15 of the shaft 12 slidably.

The side plates 3 of the stator are provided with oil ports 31, communicating with pipes 32, the pipes being adapted to supply 100 a lubricant for lubricating and cooling the working parts of the engine.

Let it be supposed that the parts are arranged as shown in Fig. 2, and that a charge has been compressed in the chamber 23. 105 When the charge in the chamber 23 is ignited, the pistons tend to separate, the blocks 28 pivoting on their mountings 29 and sliding on the arms 15 of the shaft 12, rotation being imparted to the shaft in this 110 way. The charge in the chamber 23 tends to expand through an arc of 180 degrees,

and through the next 180 degrees, the chamber 23 contracts to assume the proportions shown in Fig. 2. During this last specified operation, the exhaust leaves by way of the 5 port 26. During the next 180 degrees of revolution, the chamber 23 enlarges and takes in a charge through the port 25. During the next 180 degrees of revolution, the charge is compressed, the parts assuming 10 the positions of Fig. 2, whereupon the charge is again ignited. The operation above described has been confined to but one of the chambers 23, but it is obvious that a chamber 23 is formed at both ends of the piston 15 tons, one chamber 23 enlarging under the action of the expanding charge, while the other chamber 23 is contracting to force out the exhaust through the port 26. The moving blocks 28, coöoperating with the ports 31 20 and the pipes 32, aid in drawing in and expelling the lubricant, thus keeping the working parts of the engine lubricated and cooled.

The ports 25 and 26 are controlled by 25 valve mechanisms of any desired sort, which may be located in the casing 7, but since any specific valve mechanism cannot be claimed in the rotary engine construction, no valve mechanism adapted for the ends 30 in view has been shown.

As shown in Figs. 3, 4, 5 and 6, the engine includes an outer plate 33, an inner plate 34 and a ring 35 located between the plates, the parts above mentioned constituting the stator. Coöoperating with the inner plate 34 is an inner plate 36 having a ring 37 engaging an outer plate 38, the plate 36, the ring 37 and the plate 38 forming an auxiliary casing. The plate 38 has a bearing 39 carrying a bushing 57. The plate 33 is provided with a bearing 40.

The pistons are of the general type hereinbefore described, and therefore they need not be alluded to in great detail, each piston 45 including a body 41 and a hub 42. The expansion chamber appears at 43 and the spark plug is shown at 44. The necessary packings 45 are provided, as before. One of the pistons is carried by a solid shaft 46 50 journaled in the bearing 40. The other piston is carried by a tubular shaft 47 surrounding the shaft 46 and journaled in the hubs 48 formed on the plates 34 and 36. The shaft 47 is provided with an arm 49 55 located in the auxiliary casing above mentioned. The shaft 46 is provided with an arm 50 located in the auxiliary casing. The numeral 51 denotes a bar disposed in the auxiliary casing. The bar 51 has a longitudinal guide way 52. The numeral 53 denotes a link forming a pivotal connection between the outer end of the arm 49 and one end of the bar 51. The outer end of the arm 50 is pivoted directly to the other end of the 60 bar 51. Journaled in the bushing 57 is a 65

shaft 56, the same being mounted eccentrically with respect to the stator. The shaft 56 carries a parallel-sided block 55 mounted to slide in the guideway 52 of the link bar 51. 70

In practical operation, when the pistons are operated in the manner hereinbefore set forth, the shafts 47 and 46 will be rotated, motion being transmitted to the bar 51 by the arm 50, from the shaft 46, and motion 75 being transmitted to the bar 51, from the shaft 47, by means of the arm 49 and the link 53. When the bar 51 is operated, the block 55 slides in the guideway 52 of the bar 51 and rotary movement is imparted to 80 the shaft 56.

It will be obvious that the device forming the subject matter of this application may be used as a pump, the essential mechanical elements of the device being retained. Thus, 85 taking the structures shown in Figs. 1 and 2 as typical, the shaft 12 is power driven, the fluid which is to be pumped being sucked in as the chamber 23 increases in size, and being expelled as the chamber 23 decreases in 90 size.

Having thus described the invention, what is claimed is:—

1. In a device of the class described, a stator; a pair of pistons having orbital movement in the stator and conforming to the inner curve of the stator, the ends of the pistons being provided with coöoperating recesses extended entirely thereacross and defining expansion chambers when the ends 100 of the pistons abut, the expansion chambers being open at their ends throughout the entire diameter of the expansion chambers, the pistons being relatively movable circumferentially of the stator to enlarge and 105 diminish the chambers, the stator having in one side, an inlet port, and being provided in one side with an exhaust port, the ports communicating at different times with each chamber; a shaft journaled in the stator; 110 means for operatively connecting the shaft with the pistons; and an ignition device carried by one side of the stator and co-operating with the chambers, throughout the entire diameter of each chamber. 115

2. In a device of the class described, a stator; a pair of pistons having orbital movement in the stator, the ends of the pistons coöperating to form expansion chambers, the pistons being relatively movable 120 circumferentially of the stator to enlarge and diminish the chambers, the stator having an inlet port and exhaust port communicating at different times with each chamber; a shaft journaled in the stator; means for operatively connecting the shaft with the pistons; and lubricant conveying pipes communicating with the stator, said means being effective to cause a circulation of lubricant, by way of said pipes, thereby to 125 130

effect a lubrication and a cooling of the structure.

3. In a device of the class described, a stator; a pair of pistons having orbital 5 movement in the stator, the ends of the pistons coöperating to form expansion chambers, the pistons being relatively movable circumferentially of the stator to enlarge and diminish the chambers, the stator hav-
10 ing an inlet port and an exhaust port communicating at different times with each chamber; a shaft journaled in the stator and having arms; blocks pivoted to the pis-

tons and receiving the arms slidably; and lubricant-conveying means communicating 15 with the stator, the blocks being movable to cause a circulation of the lubricant, by way of said means, thereby to effect a lubrication and a cooling of the structure.

In testimony that I claim the foregoing 20 as my own, I have hereto affixed my signature in the presence of two witnesses.

LESLIE M. SHERIDAN.
